UNITED STATES PATENT OFFICE.

LESTER S. KEILHOLTZ, OF DAYTON, OHIO, ASSIGNOR, BY MESNE ASSIGNMENTS, TO
DELCO-LIGHT COMPANY, OF DAYTON, OHIO, A CORPORATION OF DELAWARE.

POWER PLANT.

Application filed March 28, 1918. Serial No. 225,312.

To all whom it may concern:

Be it known that I, LESTER S. KEILHOLTZ, a citizen of the United States of America, residing at Dayton, county of Montgomery, 5 State of Ohio, have invented certain new and useful Improvements in Power Plants, of which the following is a full, clear, and exact description.

This invention relates to engines of the 10 internal combustion or explosion type, and has for an object the provision of improved fuel supply devices. More particularly, an object of the invention is to provide a unitary device in which the fuel-pump chamber, fuel filter chamber, fuel reservoir, air 15 passage to the engine intake, and other associated parts are formed in a casting in order to render the device more compact and to reduce the number of joints in the 20 fuel-supply circuit to a minimum.

Another object of this invention is the provision of a casting which is a coupling between the breather tube and the engine intake, which is adapted to be connected with 25 a remote source of fuel supply and which contains the fuel-pump and associated means for delivering the fuel from the source of fuel supply to the engine intake.

Still another object of this invention is 30 the operation of the fuel-pump from the rocker arm of the valve gear by means of pivotally connected members including a lever which may be manually moved from its fulcrum whereby the pump may be manually operated while permitting the connection between the pump and engine to 35 remain intact.

Further objects and advantages of the 40 present invention will be apparent from the following description of a preferred embodiment thereof, reference being had to the accompanying drawings.

In the drawings:

Fig. 1 is a view taken at the flywheel end, 45 of an engine embodying the present invention certain parts being shown in elevation and certain parts being in section for sake of clearness;

Fig. 2 is a plan view of the fuel reservoir and carbureting chamber with the cover removed to show part of the interior arrangement;

Fig. 3 is a sectional view taken on line 5-5 of Fig. 2;

Fig. 4 is a sectional view taken on line 55 6-6 of Fig. 2.

Referring to the drawings, 20 designates a base supporting a crank case casting 21. Casting 21 comprises the crank case 21^a, which includes a lubricant reservoir located 60 at the bottom of the casting, and a chamber extending upwardly from the reservoir which provides a housing for the crank, connecting rod and other moving parts. The crank casting 21 also includes a jacket 21^b 65 surrounding the upper portion of the crank case, said jacket terminating with a circular flange 21^c substantially on the level with the upper end of the crank case 21^a, and cooperating with crank case 21^a to form an 70 annular passage surrounding said crank case for a purpose to be described.

Crank case casting 21 supports crank shaft 24 which carries flywheel 25 provided with fan blades 26, and shaft 24 is provided 75 with crank 27 formed integral therewith. Crank case 21^a supports cylinder 40, in which is mounted for reciprocation a piston 41, connected by means of connecting rod 42 to crank 27. Cylinder 40 is provided with 80 radiating fins 43.

Cylinder head 44 is supported on the upper end of cylinder 40 and is provided with combustion chamber 44^b, an inlet passage 45, and an exhaust passage 46, to 85 which an exhaust pipe 47 may be secured. Cylinder head 44 is provided with radiating fins 48 and 49.

Cylinder head 44 is provided with an intake valve 57 and an exhaust valve 58 which 90 are guided in sleeves 44^d and normally held in seated position upon valve seats 44^e by means of springs 59 and 60, respectively. The inlet and exhaust valves are unseated by suitably supported rocker arms 55 and 95 56, respectively, which may be actuated from the cam shaft 65 by any desired means, as for example, push rods 61 and 62 which are lifted by cams 63 and 64, respectively, carried on the cam shaft 65. Cam shaft 65 100 is supported for rotation by bearing 66 mounted in the crank case casting 21, and carries a gear 68 cooperating with gear 69 mounted on shaft 24.

The valve gear, including the rocker arms 105 and push rods, are preferably mounted on the engine in a manner such that the clearance between the end of the valve and the

rocker arm will remain the same for all temperatures to which the engine is subjected in operation, whereby correct valve timing is maintained for all temperatures and unnecessary valve noise is eliminated. The manner by which this result is accomplished is described and claimed in my divisional application, Serial Number 305,310, filed June 19, 1919, to which reference is made for further details thereof.

Gear 71 mounted upon casting 21 cooperates with gear 70 carried by the crank shaft 24 for the purpose of throwing oil which is contained in the lower part of the 15 crank case 21^a, to the various moving parts contained within the crank case. Oil may be introduced through pipe 72 and drained off through pipe 73. Indicator 74 cooperating with float 75 shows the level of the oil in 20 the crank case.

Crank case casting 21 supports jacket 76 which surrounds the sides of the cylinder and cylinder head; and jacket 76 supports jacket 77 which is opened at its upper end 25 and surrounds the upper portion of the cylinder head and parts supported thereon. As the flywheel rotates the fan blades 26 carried thereby will cause the circulation of air down through jacket 77, 76 and through 30 the space between the jacket 21^b and crank case 21^a, and out of the engine between the fan blades.

Crank case casting 21 is provided with a passage 80, which leads into breather or 35 breather tube 81 comprising a base 82 upon which is supported an outer casing 83, provided with holes 84 located near the lower end thereof. Base 82 is provided with a valve 40 normally held down by gravity or by means of spring 86 upon a valve seat 87. The function of the valve 85 is to normally close the passage from the crank case to the breather. An inner tube 88 is mounted on base 82 concentrically with relation to casing 83. Tube 88 is open at both ends and is provided with a side opening 89 near the upper end. Fuel chamber fixture 90 which is supported by means of cylinder head 44, serves as a cap for upper end of the breather, 45 and closes the upper end of the space between the outer casing 83 and the inner tube 88, and serves to form a continuation of the passage from inner tube 88 to the inlet pipe 45 in the cylinder head. The construction 50 of the breather is substantially the same as that described in the patent to Charles F. Kettering, No. 1,380,974, dated June 7, 1921, and since said breather forms no part of the present invention, further description is considered unnecessary. The operation of the 55 breather may be briefly stated as consisting first, of driving out on the explosion stroke and upwardly through valve 85 into inner tube 88, out through opening 89, as indicated 60 by arrow 89^a, the vaporous contents of the

crank case including unburnt fuel which has leaked past the piston rings. Before the aforesaid vapors can pass downwardly and reach the bottom of outer casing, the intake stroke of the piston will have taken 70 place. At this time the contents of casing 83 will be sucked upwardly through opening 89, as indicated by arrow 89^b, and will pass through passages 96, 97 and 98 in fuel chamber fixture 90 to be described and into 75 intake passage 45. In this manner the escape of smoke and obnoxious fumes from the crank case and breather tube into the room is prevented.

The fuel chamber fixture or casting 90 80 will now be described. Casting 90 comprises a flange 90^a by means of which said casting is secured to cylinder head 44. The lower portion of casting 90 is provided with an outwardly extending portion 91 which is 85 provided with a circular recess 92 for the reception of the upper end of the inner tube 88 of breather 81, which, when assembled, abuts against the shoulder 93 formed in said casting 90. The portion 91 is provided with 90 an annular recess 94 containing a felt packing ring 95, for the reception of the upper end of the outer casing 83. The passage 96 forms a continuation of the recess 92 and serves to connect the breather with the engine intake, and includes a carbureting or 95 mixing chamber comprising venturi passages 97 and 98. A gate throttle-valve 99 located in recess 99^a is mounted for rotation upon a stub shaft 100 which carries a throttle lever 101, which may be moved manually or by any suitable device.

Casting 90 is provided with a cylinder 102 in which reciprocates a piston 103 having passage ways 104 and 105 bored therein. The lower end of piston 103 has passage 104 provided with a check valve 106. Upon the reciprocation of the piston 103, fuel will be drawn up from a source of supply, not shown, through pipe 107 around 100 an annular recess 109 in filter plug 108, through hole 110 leading to the interior of said plug 108, and through screen 111 carried thereby into filter chamber 112. From 105 chamber 112, fuel will pass during the upward stroke of the piston around check valve 113, and into cylinder 102. Upon the downward movement of the piston, fuel will pass upwardly into passage 104, and, when this passage has been filled, will flow 110 outwardly through passage 105 into chamber 125 and into fuel reservoir 126.

The upper end of piston 103 is bifurcated at 114 to receive lever 116 connected by means of pin 115 to piston 103. The lever 116 is fulcrumed within the notch 118 provided in fulcrum post 117, and is connected by means of link 119 and stud 120 with rocker arm 55. The spring 121, connected at one end with lever 116 and, at 130

- the other, with a lug 122 projecting from casting 90 serves normally to retain the piston in its downward position, and to hold lever 116 upon its fulcrum. It will be seen that there has been provided a simple and convenient device for operating the pump piston from a moving part of the engine. Attention is called to the fact that the pump may be operated manually when the engine is at rest, without making any disconnections. The pump piston 103 may be reciprocated manually by rocking lever 116 about its connection with link 119 as a fulcrum, since the connection between the lever and fulcrum is not permanent, the spring 121 serving to yieldingly hold the lever in position. The bifurcation in post 117 serves as a guide for lever 116 during manual operation.
- When a certain level in the fuel reservoir 126 has been obtained, the surplus fuel may flow over waste weir 126^a to overflow chamber 127 and passage 128 to the source of supply. The pump is so constructed that there will always be a surplus of fuel passing over the waste weir beyond that which is required for the operation of the engine, so that a fuel level will be maintained practically constant. From reservoir 126 the fuel-charge will pass through opening 129 into the fuel chamber 130, the bottom of which is slightly below the level of the fuel in the reservoir. By reason of the constant level maintained in said reservoir, a constant quantity of fuel necessary for each charge will be maintained in said fuel-charge chamber 130. Upon the suction stroke of the engine, this fuel charge will be sucked out of chamber 130, through passage 131, and into venturi passages 97 and 98, where it will mix with the contents of the breather tube which has been drawn in, as described.
- The casting 90 is provided with a recess 132 for the reception of fuel for priming which may pass downwardly through a passage 133 containing a wick, and into passage 97.
- The fuel reservoir is provided with a cover 136 held in position upon the top of the casting by means of a spring 135 which is retained between the shoulder, formed on fulcrumed post 117, and the cover 136.
- The passage 96 is provided with a butterfly valve 137 mounted upon shaft 138 which carries a lever 139, by means of which the position of said valve may be changed to vary the proportion of the fuel mixture.
- It will be apparent from the foregoing description that the fuel chamber casting 90 provides an enclosure for the upper end of the breather, and forms the stationary elements of the pump, a fuel reservoir and overflow chamber, a chamber for accumulation of the fuel charge, and a fuel mix-
- ing chamber; and provides a support for the throttle and mixture controlling valves and the pump lever. By locating the fuel pump within the fuel chamber casting, the number of connections between the source of fuel supply and the fuel chamber is reduced to a minimum, resulting in the prevention of loss of fuel and the removal of danger from fire, ordinarily due to leaky connections. By combining a number of elements in one unitary structure, and thereby by reducing the number of parts in the manner described, a maximum of economy and simplicity of construction has been obtained.
- As a means of control for the throttle valve, there is provided a solenoid magnet 140, which cooperates with a solenoid armature 141, which is connected with throttle lever 101. The position of the throttle lever may thus be controlled electrically according to the amount of electrical energy delivered to the solenoid magnet. This controlling device, however, forms no part of the present invention but is described and claimed in the copending application of Charles F. Kettering, Serial No. 226,986, filed April 6, 1918.
- While the form of mechanism herein shown and described constitutes a preferred embodiment of one form of the invention, it is to be understood that other forms might be adopted and various changes and alterations made in the shape, size, and proportion of the elements therein without departing from the spirit and scope of the invention.
- What I claim is as follows:
1. In a device of the kind described, the combination with an internal-combustion engine having an intake; of a pump communicating with the intake, and having cooperating stationary and movable elements; a fulcrum; a lever connected to the movable element and seated upon the fulcrum; yielding means normally holding the lever on the fulcrum; and means connecting the lever with a moving part of the engine.
  2. In a device of the kind described, the combination with an internal-combustion engine having an intake; of a pump communicating with the intake, and comprising cooperating stationary and movable elements; a fulcrum; a lever attached at one end of the movable element and normally seated upon the fulcrum; a spring normally holding the lever on the fulcrum; and a link adapted to connect the lever with a moving part of the engine.
  3. In a device of the kind described, the combination with an engine having an intake, of a fuel pump communicating with the intake, and including cooperating stationary and movable elements; and means positively connecting the movable element with a moving part of the engine, said connecting means

comprising a pivoted element adapted to be moved from its normal fulcrum for manually operating the pump.

4. In a device of the kind described, the combination with an engine having an intake, of a fuel pump communicating with the intake, and including cooperating stationary and movable elements; and means positively connecting the movable element 10 with a moving part of the engine, said connecting means comprising a rocking member adapted to be moved from its normal fulcrum for manually operating the pump.

5. In a device of the kind described, the combination with an engine having an intake, of a fuel pump communicating with the intake, and including cooperating stationary and movable elements; mechanism 15 providing a positive inextensible inextensible connection between the movable element and a moving part of the engine, said mechanism being adapted for manual movement independently of the engine movement while maintaining intact its connection with 20 said movable element and said moving engine part.

6. In a device of the kind described, the combination with an engine having an intake, of a fuel pump communicating with the 30 intake, and including cooperating stationary and movable elements; a linkage positively and pivotally connected to the movable element and to a moving part of the engine, said linkage including a lever normally fulcrumed on a fixed part of the engine; and means for actuating said linkage independently of the engine movement to operate the fuel pump while maintaining intact its connection with said movable element and said 35 moving engine part.

7. In a device of the kind described, the combination with an engine having an intake, of a fuel pump communicating with the intake, and including cooperating stationary and movable elements; a linkage 45 positively and pivotally connected to the movable element and to a moving part of the engine, said linkage including a lever normally fulcrumed on a fixed part of the engine and a link connecting said lever directly to the rocker arm of the engine valve gear; and means for actuating said linkage independently of the engine movement to operate the fuel pump while maintaining intact its connection with said movable element and said moving engine part.

8. In a device of the kind described, the combination with an internal-combustion engine having a breather connected with the 50 crank case and including outer and inner walls; of a fuel chamber casting adapted to be connected with the engine intake and to form a closure for the space included between the walls of the breather into the engine intake, said casting including a mix-

ing chamber, and provisions in the casting for delivering a constant quantity of fuel to the mixing chamber at each suction stroke of the engine.

9. In a device of the kind described, the combination with an internal-combustion engine having a crank case, an intake, and a breather extending vertically from the crank case; of a fuel chamber casting adapted to be connected with the intake and 70 breather and to form a closure for the upper end thereof, said casting including a passage from the breather to the intake which includes a mixing chamber and provisions in the casting for delivering a constant 80 quantity of fuel to the mixing chamber at each suction stroke of the engine.

10. In a device of the character described, the combination with an internal-combustion engine having an intake, a crank case 85 and a breather pipe connected to and extending vertically from the crank case; of a fuel-chamber casting connected with the engine intake and the breather pipe and forming a closure for the adjacent end 90 thereof, said casting comprising an air passage from the breather pipe to the intake including a mixing chamber, a fuel reservoir 95 communicating with the passage, and a fuel pump adapted to pump fuel from a remote source of fuel supply into the fuel reservoir.

11. In a device of the character described, the combination with an internal-combustion engine having an intake and a breather tube; of a fuel-chamber casting connected 100 with the engine intake and the breather pipe and forming a closure for the adjacent end thereof, said casting comprising an air passage from the breather pipe to the intake including a mixing chamber, a fuel reservoir 105 communicating with the passage, and means adapted to pump fuel from a remote source of fuel supply into the fuel reservoir.

12. In a device of the character described, the combination with an internal-combustion engine having an intake and a breather tube; of a fuel-chamber casting connected 110 with the engine intake and the breather pipe and forming a closure for the adjacent end thereof, said casting comprising an air passage from the breather pipe to the intake including a mixing chamber, a fuel-charge 115 chamber communicating with the mixing chamber, a fuel reservoir connected with the fuel-charge chamber, and engine-actuated means for replenishing said fuel reservoir.

13. In a device of the kind described, the combination with an internal-combustion engine having an intake; of a unitary fuel-chamber member adapted to be attached to the engine intake, and formed to provide a fuel filter chamber, a fuel-pump 125 130

cylinder, a reservoir connected with the pump cylinder, a fuel-charge receiving chamber communicating with the reservoir, a waste weir for the reservoir, and air passage leading from the interior of the fuel-chamber member to the engine intake and including a venturi passage forming a mixing chamber, and a passage from the fuel-charge chamber to the mixing chamber; a throttle valve mounted for movement upon the fuel-chamber member and adapted to close the air passage between the mixing chamber and the engine intake; a piston adapted to reciprocate in the pump cylinder; and means for operating the piston.

10. In a device of the kind described, the combination with an internal-combustion engine having an intake and breather; of a unitary fuel-chamber member, adapted to 20 be attached to the intake and to form the upper-end part of the breather, and also formed to provide a fuel-filter chamber, a fuel-pump cylinder, a reservoir connected with the pump cylinder, a fuel-charge receiving chamber connected with the reservoir, a waste weir for the reservoir a passage from the breather to the intake, including a venturi passage forming a mixing chamber, and a passage leading from the fuel-charge chamber to the mixing chamber; a throttle valve in the air passage, a piston adapted to reciprocate in the cylinder; and means for operating the piston.

14. In a device of the kind described, the combination with an internal-combustion engine having an intake and breather; of a unitary fuel-chamber member, adapted to 20 be attached to the intake and to form the
